UNITED STATES PATENT OFFICE.

JAMES I. FLANAGEN, OF PHILADELPHIA, PENNSYLVANIA.

HANDLE FOR WASHBOILERS, PAILS, &c.

SPECIFICATION forming part of Letters Patent No. 636,784, dated November 14, 1899.

Application filed April 12, 1899. Serial No. 712,696. (No model.)

To all whom it may concern:

Be it known that I, JAMES I. FLANAGEN, a citizen of the United States, residing in the city and county of Philadelphia, State of Pennsylvania, have invented a new and useful Improvement in Handles for Washboilers, Pails, &c., which improvement is fully set forth in the following specification and accompanying drawings.

10 My invention consists, first, of a handle formed of a grip and side arms, the latter being constructed of sheet metal stiffened by beads, whereby the same is light, strong, durable, and inexpensive.

15 It also consists in providing the arms with flanges which embrace and tightly hold the shoulders or ridges on the grip, forming a strong connection between the parts.

Figure 1 represents a perspective view of a 20 handle embodying my invention. Fig. 2 represents a section thereof on line $x-x$, Fig. 1, on an enlarged scale. Fig. 3 represents a section on line $y-y$, Fig. 1. Fig. 4 represents a section on line $z-z$, Fig. 1. Fig. 5 represents 25 a section of a portion, showing one of the eyes in condition prior to being interlocked with the grip. Fig. 6 represents a side elevation of the handle. Fig. 7 represents a section of a modification.

30 Similar letters of reference indicate corresponding parts in the figures.

Referring to the drawings, A designates a handle formed of the grip A' and side arms B. The grip, preferably constructed of wood, 35 has circumferential shoulders or ridges C thereon near the edges thereof. The arms are constructed of sheet metal, each with an eye D at one end and ears E at the other end, the latter having openings F therein for rivets or 40 pins, by which the handle may be attached to a washboiler or other vessel, pail, tub, &c.

Extending around the sides of the bodies 45 of the arms are beads G, and around the ears thereof are beads H, the same being struck up, crimping the metal and serving to stiffen the same, whereby the arms and ears, though light in weight, are vastly strengthened, and their durability is greatly increased. Between the ears E of each arm there is the bead J as 50 a divisional line between said ears, the same extending into the body of the arm and serv-

ing to strengthen said ears at the place of occupation of said line and body.

On the sides of the eyes D, which latter embrace the peripheries of the ridges C, are 55 flanges K, which are inturned and embrace the sides of said ridges, they being swaged thereon, thus firmly interlocking the arms with said grip and preventing wrenching off of either part when subjected to strain or disconnection of the grip from the arms or, vice versa, when the handle is in use and receives the weight transmitted to it from the boiler, pail, &c.

The sides of the arms around the beads are 60 provided with inturned lips M, thus doubling said sides and presenting a rounded edge, which increases the strength of said sides and removes the raw edges from exposure and liability to cut the hand of the one using the 70 handle.

In order to prevent rotary motion of the grip, the ears have spurs or studs N punched out of the same by any suitable tool and entering the grip, the effect of which is evident. 75 If desired, nails may be driven through said spurs or studs into the grip to increase the hold of the grip in the eyes; but to this I do not limit myself. As another form of locking the eyes on the ridges the latter may be 80 circumferentially grooved and the eyes depressed or formed with inturned beads P, which enter said grooves and embrace the sides of said grooves, as shown in Fig. 7.

Having thus described my invention, what 85 I claim as new, and desire to secure by Letters Patent, is—

1. In a handle, grip-carrying arms, a grip connecting the outer ends of said arms, said arms having beads on the edges thereof, and 90 lips inturned from said beads at the outer end portions of said arms adjacent the grip, doubling said edges.

2. In a handle, side arms provided at their outer ends with eyes, a grip having its end 95 portions situated within said eyes, the end portions of said grip being provided with a shoulder, the interior faces of said eyes engaging the outer faces of the grip exterior to said shoulder, and flanges extending inwardly 100 of the interior faces of the eyes and having lateral engagement with said shoulders.

3. In a handle, side arms provided at their outer ends with eyes, a grip having its end portions situated within said eyes, the end portions of said grip being provided with a shoulder, the interior faces of said eyes engaging the outer faces of the grip exterior to said shoulder, and flanges extending inwardly of the interior faces of the eyes and having lateral engagement with said shoulders, said eyes being provided with spurs or studs engaging said grip.

JAMES I. FLANAGEN.
